T. W. PROSSER ET AL

HOSIERY FINISHING APPARATUS

Filed May 6, 1926

UNITED STATES PATENT OFFICE.

THOMAS W. PROSSER AND JOHN H. WAHLEBECK, OF KANKAKEE, ILLINOIS, AS
SIGNORS TO PARAMOUNT TEXTILE MACHINERY CO., OF CHICAGO, ILLINOIS, A
CORPORATION OF ILLINOIS.

HOSIERY-FINISHING APPARATUS.

Application filed May 6, 1926. Serial No. 107,165.

This invention primarily relates to hosiery finishing apparatus; it has especial reference to a system involving primary and secondary heating agents, the latter being maintained in one or more closed forming instrumentalities or so-called drying and shaping forms, the primary heating agent being utilized to impart its heat to the secondary heating agent; and it contemplates a system in which is employed a conduit for the primary heating agent, this latter (by its presence in the conduit) transmitting heat to the secondary heating agent in the form, whereby its walls are heated to dry hosiery superposed thereon.

Present-day practice of finishing hosiery—drying, shaping and creasing it—involves, for the most part, the employment of a series of forms provided with crease-producing edges and adapted to be interiorally heated. The forms are usually mounted in line on a table, and the hosiery is placed on the forms by an operator and then, when finished, stripped therefrom. This operation is frequently called "boarding". That is, each hosiery-article is placed on a form by an operator who moves successively from form to form. The forms are heated to effect a drying and setting of the fabric simultaneously with the shaping and creasing thereof.

A heating medium, such as steam, is employed to heat the forms; but, where the hosiery is of fine texture—sheer—these forms, as heated by steam, are usually too hot so that the damp hosiery is thereby subjected to a rather high degree of heat and too high to insure the best results. Due to premature drying and setting of the fabric, undesirable creasing and marking of the hosiery-article occurs. It is not possible, however, satisfactorily to operate the forms by steam below a certain temperature, and even that is too high for desirable results.

More recently, it has been found that where a medium, such as water, is utilized for imparting heat to the walls of the form, a lower and more uniform temperature can be maintained in those walls, with resultant improvement in the "boarding" operations.

Various systems for utilizing this principle have been devised, whereby water is availed of as a secondary heating agent, it receiving its heat from a primary heating agent—in the form of steam—which is brought into association with the secondary heating agent. Our inventive-concept resides in a novel system of associating these two heating agents within the form, itself. It will be understood that we do not herein broadly claim inventorship of the use, in conjunction with hosiery drying and shaping forms, of primary and secondary heating agents involving the use, say, of steam and water, respectively; but we do assert inventorship of a system which involves, generally, maintaining a body of the secondary heating agent in the form as a confined heating body and subjecting it, there, to the heating action of the primary heating agent, whereby the secondary agent is heated so that it, in turn, will uniformly impart heat to the walls of the form and, thus, to hosiery superposed thereon.

In a more specific aspect, the invention resides in providing a conduit for the primary heating agent and in mounting on another conduit which encompasses that for conveying the primary heating agent one or more of the hosiery-drying forms, these containing a body of the secondary heating agent, there being within each form an extension of the first-mentioned conduit whereby the primary heating agent is conducted into the form but is not brought into direct association with the secondary agent therein. The walls of the extension are utilized to impart heat to the secondary heating agent within the form, and this agent, in turn, imparts its heat to the walls of the form to dry hosiery superposed thereon.

In order that the invention may be better comprehended, we have revealed the same in the accompanying drawings; it being understood, however, that in disclosing the same in a specific embodiment, we do not thereby intend that it is limited to that embodiment. Furthermore, it is to be understood that it is susceptible of a wide range of variation and modification without departing from

the spirit of the invention or sacrificing any of its salient principles and underlying details.

In these drawings:

5 Figure 1 is a view in sectional elevation of a hosiery drying and shaping apparatus embodying our invention;

Figure 2 is a view in horizontal, transverse section thereof, on the line 2—2,

10 Fig. 1;

Figure 3 is a similar view on the line 3—3, Fig. 1; and

15 Fig. 4 is a fragmentary view in central vertical section, on an enlarged scale, showing the manner of associating certain components of the structure.

20 Referring to these drawings, the reference-character 1 designates, generally, a hosiery-finishing instrumentality of the known Paramount type, this being shown and described in United States patent of George Collis, No. 1,204,945, dated May 14, 1916.

25 This form, preferably and as shown, is hollow to provide a heating-chamber 2 constituted (in part) by the side walls 3 and a partition 4 which divides the chamber into channels 5 and 6. The construction is such that, for all practical purposes, the form is 30 closed and adapted to confine a body of secondary heating agent which, in this instance, is water, though it may be alcohol, an oleaginous liquid, a salt in solution, or any other appropriate media.

35 For a purpose presently to be explained, the partition, near its lower end, is provided with an opening 8.

40 In practice, a series of these forms will usually be mounted in alinement and, preferably and as here shown, in communication with a conduit 9, this being supported, in any appropriate manner, in a table (not shown).

45 Interposed between the base 10 of the form and the conduit 9 is a coupling-member 11. Each of the forms is secured thereto by bolts 12. The coupling is, itself, secured to the conduit 9 by bolts 13.

50 The channels 5 and 6 communicate with passageways 14 and 14, respectively, in the base of the form; and these, in turn, register with but are separated from passageways 15 and 16, respectively, in the coupling member. The conduit 9, adjacent the mounting of each form thereon, is provided with an aperture 17 which registers with the passageway 15 in the coupling-member.

Disposed between the lower face of the base 10 of the form and the upper face of the coupling-member are a metal plate 18, a gasket 19—preferably of rubber—and a second gasket 20, preferably of asbestos or similar material; all of these elements being held in operative association with the form and coupling-member by the bolts 12.

It will be noted that, as the plate 18 and the gaskets 19 and 20 cover the passageway 14, they interrupt communication between the passageways 14 and 15; and, likewise, the passageways 14 and 16.

70

Interposed between the lower face of the coupling-member and the proximate surface of the conduit 9 is a gasket 21, preferably of asbestos.

75 Threaded into the plate 18 is a housing or return-pipe 22, for a purpose presently to be explained.

80 Disposed within the conduit 9 is a second conduit or pipe 23 which extends out of the conduit 9 through endfittings 24, and is connected at one end, to a thermostatically-controlled valve 25, of any appropriate type and operating in the well-known manner. Communicating with the valve 25 is a steam pipe 26 which extends to a suitable source 85 of steam supply (not shown) and which is controlled by a valve 27.

85 Upstanding from the pipe 23 and extending through the aperture 17 in the conduit 9 and through the channel 15 in the coupling 90 11 is what we shall herein refer to as an extension 28 of the conduit 23, it being, itself, a pipe which extends into the return-pipe 22 in the channel 5.

95 Preferably and as shown, the housing or return-pipe 22 is of diametral dimension larger than that of the pipe 28 to provide an annular space 28^a and is in contact with the body of water in the channel 5. This pipe 28 and the pipe 22 are of a height 100 determined by the temperature desired in the secondary heating agent and the temperature supplied thereto by the primary heating agent; the less difference between the two temperatures the greater should be 105 the heating surface of the pipe 22.

110 The steam-pipe 23 connects, beyond the fitting 24, with a water-leg 29, this in turn being connected to a trap 30 and provided with a pet-cock 31 for draining water from the water-leg.

115 Mounted on the conduit 9 is a thermometer 32.

120 The plate 18 is provided with an opening 33, in which a closure-plug 34 is threaded. By these means, the secondary fluid is introduced into and sealed in each form before the form is mounted on the conduit, this operation being accomplished when the form is upside down.

125 When these instrumentalities have been assembled, as here illustrated, and it is desired to operate the apparatus, the valve 27 is opened to permit steam to pass through the thermostatically-controlled valve 25 into the conduit 23 and, thence, through the extension 28 into the return-pipe 22, after which any vapor condensed can return through the passageway 28^a and, thence, in the space 28^a surrounding the conduit 23 130

leading (through the water-leg 29) to the trap 30. Any condensation coming with the steam into the conduit 23 can also pass through one of the members of the water-leg and, thence, also to the trap. The thermostatically-controlled valve 25 may be set to maintain the temperature of the secondary heating agent confined in the form 1 at any desired degree, according to the texture 5 of the fabric being dried. The opening 33 in the plate 18 permits the introduction of the secondary heating agent into the chamber 2. This opening having been sealed with the plug 34, the secondary heating agent 10 thereupon operates automatically. It will be noted that, in this instance, heating of the secondary agent is effected within the form itself, by reason of the fact that the primary heating agent is, through the instrumentalities 15 22 and 28, disposed within the form and, thus, provides for transmission from the primary heating agent of heat to the secondary heating agent.

It is to be understood that the aggregate 25 cross-sectional area of the pipes 22 in the several forms should not exceed the cross-sectional area of the conduit 23, thereby to insure that a flow of steam will be supplied to the interior of each form and uniform 30 heating thereby be effected.

It will be observed that the members 22 and 28^a by reason of their relation to each other and the connection of the member 28^a to the conduit 23, constitute a heater for the 35 heating agent in the channel 5; that this heater is disposed on one side only of the partition 4, in consequence of which the liquid in the channel 5, becoming heated, rises to the top of the form, causing another portion of the liquid to descend in the channel 6 on the opposite side of the partition and, thence, through the opening 8 in the partition 4, whereupon it re-enters the channel 5; and that, thus, circulation within 40 45 the form is established, and is availed of to represent the liquid to the influence of the heater in the channel 5. It will also be noted that the lower portion of the form, adjacent the channel 14 and opening 8, is insulated as completely as possible by reason of 50 55 the interpositioning of the gasket 20 and the provision of the air space constituted in the channel 16 and which is closed at its upper and lower ends by the gaskets 20 and 21, whereby transmission of heat to the descending liquid in the channel 6 is prevented and which might interfere with the circulation of the liquid.

So far as we are aware, we are the first to 60 propose confining, in a forming-instrumentality, a body of fluid having the dual function of readily and indirectly absorbing heat and distributing and disseminating it through the walls of the instrumentality to 65 a fabric-article superposed thereon, and dis-

posing within the instrumentality a conduit for a primary heating-fluid (such as steam or hot water) adapted to impart its heat indirectly, only, to the confined fluid; the exchange of all heat-units between the heating-fluids being effected within the instrumentality but, always, through a separating wall, such as the wall of the conduit, so that the heat absorbed by the instrumentality is entirely from the secondary heating-fluid—as 70 the distributing-medium—and not at all from the primary heating-fluid because the secondary-fluid is interposed between it and the heat-absorbing wall of the instrumentality. Even though the primary heating-fluid operates within the instrumentality, it is not in direct association with the secondary-fluid; it is separated therefrom; and it, thus, imparts its heat to the walls of the conduit 22 which, in turn, transmits the heat 75 to the secondary-fluid and this, in turn, uniformly distributes the heat-units to the walls of the forming-instrumentality. Were the primary heating-agent in direct association with the confined fluid, it might more or less 80 affect the constituents thereof and eventually render it ineffective to distribute heat to the walls of the forming-instrumentality. 85

Due to the location and arrangement of the primary heating-agent inside the form, circulation of the secondary heating-agent is facilitated and, thus the body of the liquid is maintained throughout at a more effective temperature, with consequent uniformity of 90 95 drying effect by the walls of the forming-instrumentality. 100

Where we have herein used the expression "distributing-medium", or similar terms, it is to be understood that these and equivalent terms comprehend and refer to what we have also herein designated the secondary heating-agent or fluid; and we intend by such terms to define the fundamental functions of that medium, namely, to absorb and distribute to and through the walls of the forming-instrumentality heat which it (the medium) has absorbed from a primary heating-agent or fluid through an interposed wall, such as the pipe 22. 105 110

Where we have herein employed the term "fluid" as applicable to the secondary heating-agent, we mean to define any fluid-medium or media that will absorb heat from the primary heating-agent and conduct it uniformly to the walls of the forming-instrumentality on which the fabric-article is superposed, when the existing temperature does not exceed approximately two hundred degrees (200°) F. (Above this temperature, the benefits of the heating-fluid seem gradually to disappear.) Thus, it will be understood that the term "fluid" not only comprehends liquid, but, if the forming-instrumentality should not be completely filled with such liquid, also vapor which arises 115 120 130

therefrom under prevailing heat conditions.
What we claim is:

1. A drying-structure including a drying-form hollow to contain a secondary heating agent adapted to impart heat through its walls to hosiery superposed thereon, a conduit for containing a primary heating agent operatively connected to and in communication with the interior of the form, and an extension of the conduit extending into the form for conveying the primary heating agent from the conduit into the form to heat the walls of the extension and thereby heat the secondary heating agent in the form. 70
2. A drying-structure including a drying-form hollow to contain a secondary heating agent adapted to impart heat through its walls to hosiery superposed thereon, a conduit for containing a primary heating agent operatively connected to and in communication with the interior of the form, an extension on the conduit and extending into the form for conveying the primary heating agent from the conduit into the form to heat the walls of the extension and thereby heat the secondary heating agent in the form, and means for withdrawing the primary heating agent when it has lost efficiency. 75
3. A drying-structure including a drying-form hollow to contain a secondary heating agent adapted to impart heat through its walls to hosiery superposed thereon, a conduit operatively connected to the form for containing a primary heating agent of a temperature normally higher than that of the secondary agent, an extension on the conduit and affording communication between the interiors of the conduit and form and adapted to conduct the primary heating agent from the conduit into the form to heat the secondary agent therein, and means associated with the extension for effecting withdrawal of the primary heating agent. 80
4. A drying-structure including a drying-form hollow to contain a secondary heating agent adapted to impart heat through its walls to hosiery superposed thereon, means for maintaining the agent in the form, a conduit operatively connected to the form for containing a primary heating agent of a temperature normally higher than that of the secondary agent, an extension on the conduit projecting into the interior of the form for conducting the primary heating agent into the form, and means extending into the form and encompassing the extension of the conduit for transmitting heat to the secondary heating agent and for withdrawing the primary heating agent from the form. 85
5. A drying-structure including a drying-form hollow to contain a secondary heating agent adapted to impart heat through its walls to hosiery superposed thereon, a conduit operatively connected to the form for containing a primary heating agent of a temperature normally higher than that of the secondary agent, a pipe extending from the conduit into the interior of the form, and a second pipe mounted in the form and encompassing the other pipe and of larger diametral dimensions than the pipe on the conduit and closed at one extremity whereby the heat of the primary heating agent conducted to it by the pipe extending from the conduit is transmitted to the secondary heating agent and the primary agent withdrawn from the form. 90
6. A drying-structure including a drying-form hollow to contain a secondary heating agent adapted to impart heat through its walls to a fabric-article superposed thereon, a partition in the form to provide two channels therein, the partition being apertured adjacent its lower end, a conduit associated with the form for containing a primary heating agent, and means associated with the conduit and with one of the channels for conducting the primary heating agent into the form and thereby heat the secondary heating agent therein and, also, to facilitate its circulation within the form. 95
7. A drying-structure including a conduit, a coupling-member mounted thereon and provided with a plurality of channels, a hollow form on the coupling-member and provided with a partition and with channels registering with the channels in the coupling-member, a heating medium in the form, means associated with the form for confining the heating medium therein, a heater extending into the form and adapted to heat the heating medium therein at one side of the partition, and means rendered active by the thermal action of the heater and operating by the force of gravity to maintain a circulation of said heating medium in the form, the channels in the form being in communication with each other to facilitate such circulation. 100
8. A drying-structure including a conduit, a coupling-member mounted thereon and provided with a plurality of channels, a hollow form on the coupling-member and provided with a partition and with channels registering with the channels in the coupling-member, a heating medium in the form, means associated with the form for confining the heating medium therein, a heater extending into the form and adapted to heat the heating medium therein at one side of the partition, means rendered active by the thermal action of the heater and operating by the force of gravity to maintain circulation of said heating medium in the form, the channels in the form being in communication with each other to facilitate such circulation, and means associated with said confining means for insulating a portion of the 105
- 110
- 115
- 120
- 125
- 130

form whereby heating of the heating medium at one stage of its circulation is prevented.

9. A drying-structure including two conduits, one within the other, a drying-form mounted on one of the conduits, a pipe upstanding from the other conduit and extending into the form, a drain-pipe encompassing said pipe, a plate associated with the lower end of the form and in which the drain-pipe is mounted, a coupling-member between the plate and the conduits, the form including a partition dividing its interior

into channels, the coupling having channels in register with those in the form, a thermal fluid confined in the form by the plate, means for closing the ends of one of the channels in the coupling-member to provide an air space, the latter, in conjunction with said means, insulating the form from the conduits, and means for connecting the form and coupling-member to one of the conduits.

In testimony whereof we affix our signatures.

THOMAS W. PROSSER.
JOHN H. WAHLBECK.
